UNITED STATES PATENT OFFICE.

PETER SORENSEN, OF NEW YORK, N. Y.

QUICK-BREAK SWITCH.

1,171,151.

Specification of Letters Patent.

Patented Feb. 8, 1916.

Application filed June 26, 1914. Serial No. 847,422.

To all whom it may concern:

Be it known that I, PETER SORENSEN, a citizen of the United States, and resident of the city of New York, borough of Brooklyn, county of Kings, and State of New York, have invented certain new and useful Improvements in Quick-Break Switches, of which the following is a specification.

This invention relates to electrical switches 10 of the quick break type. Its object is to effect the quick opening and, incidentally, the quick closing action of the electrical circuit by means of a switch comprising a minimum number of parts, all of which are 15 constructed with a view to economy in manufacture.

The invention is illustrated by the accompanying drawings in which—

Figure 1 is a top view of the switch in 20 the closed position with the supporting stud, stationary contacts, insulating base and metallic shell in section. Fig. 2 is a similar view of the switch in the open position. Fig. 3 is a side view of the switch in the open 25 position with the insulating base, metallic shell and insulating bushing in section.

In the several figures similar parts are indicated by similar characters.

The base —1—, made of porcelain or 30 other suitable insulation, carries the central stud —2— to which all of the moving parts of the switch are attached. The moving contact —3— has up turned ears at either end on which bear the stationary contacts 35 —4— and —4^a— when the switch is closed, as shown in Fig. 1. Secured to the center of moving contact —3— is a sleeve —5— which forms a bearing fitting the stud —2— so that the moving contact may oscillate 40 freely on the stud. A slotted spring washer —5^a— fitting in a groove in the lower end of the stud —2— holds the moving contact on the stud. A helical spring —6— surrounds the sleeve —5— and its ends bear on 45 opposite sides of the pin —7— secured to the moving contact —3—.

The slide bar —8— is provided with push buttons at either end for operating it and has a central slot through which the stud —2— projects. It is guided by the stud —2— and by the grooves —1^a— and —1^b—, half round in cross section, fitting the push buttons. The slide bar has formed on it an ear —8^a— and a finger —8^b—.

55 A metallic casing or shell —9—, which

is shown approximately spherical in form, incloses the switch and has holes diametrically opposite in its sides through which the push buttons project. An insulating bushing —9^b— is screwed into the ring 60 —9^a— set in a hole in the top of the shell —9—. The twin-conductors leading from the switch terminals —4^b— (one of which is shown in Fig. 3) pass through the insulating bushing.

With the switch in the closed position, as shown in Fig. 1, the quick break opening is effected by pressing on the push button on the right-hand end of the slide-bar —8—. The ear —8^a— passes under the right-hand end of the segmental flange —3^a— formed on the moving contact —3— and presses the finger —8^b— against the left-hand end of the spring —6— putting the spring under tension. As the right-hand end of the 75 spring —6— bears on the pin —7— it exerts a turning effort on the moving contact —3—. The movement of the contact —3— is, however, prevented for the moment by the engagement of the flange —3^a— with the ear 80 —8^a—. As the movement of the slide bar is continued the tension of the spring —6— is increased to the maximum in the position of the parts indicated by dot-and-dash lines 85 in Fig. 1. A slight further movement allows the flange —3^a— to pass by the right-hand end of the ear —8^a— permitting the spring —6— to snap the moving contact —3^a— from the closed position shown in Fig. 1 to the open position shown in Fig. 2. The 90 movement is stopped by the pin —7— coming in contact with the finger —8^b—.

With the switch in the open position as shown in Fig. 2 the switch is thrown to the closed position by pressing on the left-hand push button and it will be observed that the action is similar to that above described for the opening of the switch. Tension is put on the spring —6— from its right-hand end and the top of the flange —3^a— comes in 100 contact with the lower side of the ear —8^a— while the spring tension is being increased, the switch closing with a quick action when the left-hand end of the ear —8^a— clears the flange —3^a—. It will be observed that a small amount of play or lost motion is 105 allowed between the flange —3^a— and the ear —8^a— also between the finger —8^b— and the opposite ends of the spring —6—. This lost motion insures the positive engage- 110

ment and disengagement of the flange —3^a— and the ear —8^a— in both closing and opening actions.

The construction of the switch is such that the moving parts may be assembled in a group and may then be slipped on the central supporting stud which forms the only point of attachment between the fixed and moving parts of the switch. The several members making up the moving parts of the switch are so fitted together that it is impossible for any of them to become displaced. The quick action in both opening and closing is positive and no delicate adjustment is required for accomplishing it, because of the lost motion between the parts which are pointed out above.

What I claim is:

An electrical switch comprising, in combination, a pair of fixed contacts, an insulating base, a stud mounted on said base, an

oscillatory contact having an angular flange by means of which the movement thereof is controlled, a spring, a slide bar provided with a projecting portion adapted to engage 25 said flange on said oscillatory contact during the first period of its movement and also provided with a second projection adapted to engage and set said spring in its operative position and to hold said oscillatory contact 30 during said operation and on further movement to release said contact, permitting said spring to operate the same, and a part upon said oscillatory contact adapted to engage said second projection to limit the movement 35 of said oscillatory contact.

Signed at New York city, N. Y., this 23d day of June, 1914.

PETER SORENSEN.
